UNITED STATES PATENT OFFICE.

CLARENCE E. TAYLOR AND ROY WILLIAMS, OF WILMINGTON, DELAWARE.

TURBINE FOR ROTARY TUBE CLEANERS.

Application filed August 21, 1924. Serial No. 733,414.

This invention relates to improvements in turbines for tube cleaning tools of the rotary type.

The primary object of the present invention is to provide a turbine for rotary tube cleaners of compact but comparatively simple construction. The simplicity of its construction permits it to be quickly assembled or, in case of the necessity for making repairs, it can be quickly and easily taken apart to substitute new parts. Breakage of any parts, however, is not apt to occur as the device contemplated by the present invention is one that is composed of rather substantial and sturdy parts.

With this and other objects in view the invention consists in certain novel details of construction and combinations and arrangements of parts all as will hereinafter be more fully described and the novel features thereof particularly pointed out in the appended claims.

In the drawings,—

Figure 1 is a longitudinal sectional view of the turbine,

Fig. 2 is a sectional view on the line 2—2 of Fig. 1,

Fig. 3 is a transverse sectional view on the line 3—3 of Fig. 1.

The turbine of the present invention comprises an elongated cylindrical body portion preferably composed of two sections, a main section 10 and a supplementary end section 11, the section 11 being removably secured by screw threads to one end of the main section. At the end to which section 11 is attached section 10 is provided with a central bore 13 in which is secured a bushing 14 and in the inner terminal of said bore at the opposite end of said section 10 the latter is made hollow as at 12 for the accommodation or reception of parts to be presently described. At the end to which section 11 is attached the central bore 13 is enlarged somewhat to provide a socket into which a plug 15 may be screwed to close the central bore for a purpose which will presently appear. Arranged circularly around the central bore 13 is a series of air passages 16 extending axially of the body 10 and these passages emerge into the hollow portion 12 of the body. Removably inserted in the hollowed portion 12 of section 10 is an annular member 17 which has a sleeve-like portion abutting against the reduced portion of the

housing to space the annular portion of said member somewhat away from the bore 13. Said member and its sleeve-like portion have a central bore 13^a which forms a continuation of the central bore 13 in the body and journaled in the bore 13 of the body and the bore 13^a of member 17 is the rotatable shaft 18 which carries a rotor 19.

The rotor 19 is positioned at the end of the body with the annular member 17 interposed between it and the hollow portion 12 of the housing which hollow portion, after the member 17 has been inserted, forms substantially an air chamber. However, to permit the air flowing through the passages 16 to the chamber 12 to be delivered to the rotor 19 said member 17 preferably has formed in its periphery a plurality of air passages 20 which are formed at an angle to properly deliver the air to the pockets 21 formed by the blades of the rotor. A continuation 18^a of the shaft 18 is secured to the rotor 19 and carries at its outer end the cleaning tool 22, a universal joint of ordinary construction preferably being interposed between the rotor and the cleaning tool to allow the tool to properly engage the walls of the tube being cleaned.

The end section 11 of the body is hollowed out as at 24 and is provided with interior screw threads for the connection for supplying the air under pressure or other motive fluid to the body. As will be apparent, the air supplied to the interior of section 11 will pass through the passages 16 to chamber 12, thence through ports 20 in member 17, and into the pockets 21 formed by the turbine blades, the action of the air on the rotor resulting in the cleaning tool being rotated.

The shaft 18 is secured in the housing by an ordinary nut and washer 25 attached to its end and any thrust strains created by the tendency of the shaft to move longitudinally of the housing will be taken up by the annular shoulder 26 formed integral with the body 10 at the inner end of the socket in which the plug 15 is located. The socket, therefore, not only provides a shoulder which functions as a thrust bearing but it also serves the purpose of receiving the plug 15 which prevents the motive fluid entering the central bore, the entire supply of motive fluid thereby necessarily being compelled to flow through the ports or passages 16.

To disassemble the turbine it is only necessary to remove the end section 11 and then the plug 15, after which the shaft 18 is turned while the nut 25 is held stationary. This will result in the backing off of the nut and the shaft together with the rotor secured thereon will be free to be withdrawn from the housing.

What we claim is:

- 10 1. The combination of a body having a central bore of reduced diameter at one end and a plurality of air passages in said body at said end, said passages discharging into the enlarged portion of said central bore, a closure for the reduced end of said central bore, a removable member in the enlarged portion of the bore having a series of air passages therein and a central bore arranged in alinement with the reduced portion of the central bore of the body, a shaft journaled in the central bores of the body and removable member, a turbine wheel mounted on the shaft with said removable member interposed between it and the reduced portion of the bore in the body, the air passages in said removable member being
- 15
- 20
- 25

disposed at an angle to the axis of rotation of said shaft and turbine.

2. The combination of a body having a central bore of reduced diameter at one end and a plurality of air passages in said body at said end, said passages discharging into the enlarged portion of said central bore, a closure for the reduced end of said central bore, a removable member in the enlarged portion of the bore having a series of air passages therein and a central bore arranged in alinement with the reduced portion of the central bore of the body, a shaft journaled in the central bores of the body and removable member, a turbine wheel mounted on the shaft with said removable member interposed between it and the reduced portion of the bore in the body, the air passages in said removable member being disposed at an angle to the axis of rotation of said shaft and turbine, a removable head on said shaft, and an annular, integral flange in the reduced central bore of the body against which said head contacts to take up thrust strains.
